UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

BAFFLING AND SEPARATING STRUCTURE.

Application filed February 8, 1923. Serial No. 617,762.

My invention relates to circuit interrupters and more particularly to baffling and separating devices employed in combination therewith.

6 One object of my invention is to provide a baffling and separating device for a fluid-insulated circuit interrupter which separates the expelled liquid from the gaseous mixture by reason of their differences in density.

10 Another object of my invention is to provide a baffling and separating device for circuit interrupters which reduces the back pressure exerted within the circuit interrupter resulting from interference between 60 the escaping arc gases and escaping liquid.

15 It is another object of my invention to provide a baffling and separating device for circuit interrupters in which a body of liquid preceding a quantity of escaping arc gas, 65 is held suspended by the gas while the latter escapes.

20 It is also an object of my invention to provide a baffling and separating device for circuit interrupters in which the tendency to 70 atomize the liquid preceding an expanding 75 gas is minimized.

25 In baffling and separating chambers for circuit interrupters, as heretofore employed, little attention has been paid to the position 80 of the openings therein with relation to the shape and dimension of the several chambers. As a result, an unnecessarily large amount of liquid is ejected from an inner chamber of such devices to communicating 85 outer chambers, with the result that an unduly large amount of the liquid becomes atomized and is blown away by the escaping gases. Such a condition creates a back pressure which, in turn, increases the pressure 90 within the circuit interrupter.

30 In my invention, I provide a baffling and separating device comprising a central chamber directly connected to the circuit-interrupter tank and which is in communication 95 with a plurality of other chambers. The central passageway of my device is designed in such manner that the openings provided for the escape of gases are located in the lower section thereof. By this design, bodies

35 of liquid which may precede the gases into the central chamber pass by these openings and are held suspended by the escaping gases in such manner that the liquid is not blown 100 through the openings with the gases.

In the accompanying drawings:

55 Figure 1 is a view, partially in elevation and partially in section, of a circuit interrupter equipped with a baffling and separating device embodying my invention.

Fig. 2 is a transverse sectional view of the 60 baffling and separating device taken along the line II—II of Fig. 1.

Fig. 3 is a longitudinal sectional view of 65 a modified form of a baffling and separating device.

Fig. 4 is a sectional view thereof taken along the line IV—IV of Fig. 3.

Fig. 5 is a longitudinal sectional view of 70 another form of baffling and separating device.

Fig. 6 is a sectional view thereof taken along the line VI—VI of Fig. 5.

75 In the several figures of the drawing, similar reference numerals indicate the same parts.

In the preferred embodiment of my invention, a circuit interrupter 1 comprises a cover portion 2, a liquid-filled tank 3 in which is suspended a pair of relatively movable contact members 4 and a baffling and separating device 5 that is secured to the 80 cover portion 2.

The baffling and separating device 5 comprises a central passageway 6 directly connected to the interior of the circuit interrupter 1. A plurality of chambers 7 and 8 communicate with the passageway 6 through suitable openings in the dividing walls. As shown in Fig. 2, the several chambers are preferably concentric, although any 90 other construction of communicating chambers may be employed.

The wall of the passageway 6 is provided with openings 9 at points in the lower portion thereof, which are distributed around 95 the entire periphery thereof. Relatively small openings 11 may, if desired, be provided near the upper extremity of the passageway 6.

The chambers 7 and 8 are connected by 100 openings 12 which are preferably placed in staggered relation, in the direction of movement of the escaping gas, to the openings 9. The lower portions of the several chambers are connected by suitable drainage openings 105 13. An outlet 14, located at the top of the baffling and separating device 5, communicates with the atmosphere.

In the operation of the preferred embodiment of my invention, the arc gas generated during a separating movement of the relatively movable contact members 4 produces an agitation of the liquid in the tank 3, the expanding arc gases driving a portion of the liquid in advance thereof into the passageway 6. As the liquid body is rather heavy it tends, by reason of its momentum, to move longitudinally of the chamber 6 and compress whatever gases may be confined therein so that they escape through the small openings 11. However, a small portion of the liquid itself escapes through these openings in very small quantities. The shape of the passageway 6 is such that the larger mass of liquid moves by and uncovers the openings 9 through which the arc gases may escape into the chamber 7 without blowing the suspended body of liquid ahead of them with an accompanying atomization of the liquid.

By reason of the staggered relation of the openings 9 and 12, the direction of whatever particles of liquid escape through the openings 9 into the chamber 7 must be varied before they can reach the chamber 8. As a result, the particles of liquid impinge upon the wall of the chamber 7 and give up their kinetic energy, dropping to the bottom of the chamber 7 from which they return to the tank 3 through the openings 13.

Such suspended particles of liquid as are not separated from the gases in the chamber 7 pass through the openings 12 to the chamber 8 where their velocity is further checked by a change in their trajectory. When the gases reach the vent 14, they are comparatively free from suspended particles of oil.

In the form of my invention shown in Fig. 3, a baffling and separating device 21 comprises a central passage 22, chambers 23 and 24, a vent 25 and drainage passages 26.

The passageway 22 comprises an extension 27 which extends beyond the termini of the chambers 23 and 25. Openings 28 are located in the passageway 22 at points which correspond to the outer limits of the chamber 23. These openings are arranged around the entire periphery of the chamber 22. Openings 29 permit communication between the chambers 23 and 24. The openings 29 are staggered with the openings 28 in the direction of arc gas flow.

In the operation of this form of baffling and separating devices the body of liquid ejected into the passageway 22 is held in the extension 27 by the pressure of the escaping arc gases. The openings 28, being located at approximately the outer limit of the chamber 23, permit of use of substantially the whole length of chamber 23 for expansion and separating purposes. The operation of this form of my invention is otherwise the same as that described in connection with

the form of my invention shown in Figs. 1 and 2.

In the modification of my invention shown in Figs. 5 and 6, a baffling and separating device 41 comprises a central passageway 42 terminating in a reservoir 43, and chambers 44, 45 and 46. Passages 47, 48 and 49 permit communication between the passages 42-44; 44-45; 45-46; respectively. Chamber 46 terminates in the vent 51.

In the operation of the circuit interrupter equipped with this form of my invention, a body of liquid projected into the passageway 42 passes into the reservoir 43 from which it drains back into the circuit-interrupter tank. The liquid having been blown into the reservoirs 43, the passage 42 is entirely filled by arc gases so that atomization of oil as a result of forcing the gas to escape through a column of liquid is practically eliminated. The operation of this form of my invention is otherwise the same as that already described in connection with the baffling and separating devices 5 and 21.

By my invention, I have provided baffling and separating devices for circuit interrupters in which a separating chamber is so designed that the bodies of liquid normally preceding expanding arc gases, are caused to move beyond the vents provided for the escape of the gas. The liquid is held out of communication with these vents during the discharge of the gas by the pressure of the gas itself. Accordingly, there is little atomization of the liquid and there is a corresponding reduction of back pressure in the circuit interrupter and there is a large reduction in the amount of liquid ejected from the entire circuit interrupter as compared with present practice.

Various modifications in the system and arrangement and location of parts may be made within the spirit and scope of my invention and such modifications are intended to be covered by the appended claims.

I claim as my invention:

1. In a baffling and separating structure, a passageway communicating with a liquid-containing chamber, a plurality of separating chambers communicating with openings in said passageway, said openings being so located in said passageway that liquid thrown into said passageway by an expanding gas tends to move beyond said connecting openings without opposing the escape of the propelling gas through said openings.

2. In a separating structure, a passageway communicating with a pressure chamber, a second chamber communicating with openings in said passageway, the openings in said passageway being so disposed that liquid driven into the passageway by a gaseous mixture is suspended in the passageway and the gas permitted to escape from beneath the suspended liquid.

3. In a separating structure, a passageway communicating with a pressure chamber, a second chamber communicating with openings in said passageway, the openings in said passageway being so disposed that liquid driven into the passageway by a gaseous mixture is suspended in the passageway

without atomization during the escape of the gas.

In testimony whereof, I have hereunto ¹⁰ subscribed my name this first day of February 1923.

OTTO H. ESCHHOLZ.
